UNITED STATES PATENT OFFICE.

CARL D. BROWN, OF HOPEDALE, MASSACHUSETTS, ASSIGNOR TO DRAPER CORPORATION, OF HOPEDALE, MASSACHUSETTS, A CORPORATION OF MAINE.

FILLING-END HOLDER AND CUTTER FOR LOOMS.

Application filed February 9, 1925. Serial No. 7,895.

To all whom it may concern:

Be it known that I, CARL D. BROWN, a citizen of the United States, and a resident of Hopedale, county of Worcester, State of Massachusetts, have invented an Improvement in Filling-End Holders and Cutters for Looms, of which the following description, in connection with the accompanying drawing, is a specification, like characters on the drawings representing like parts.

This invention relates to the filling carrier magazine such as is employed for holding the supply of fresh filling carriers in an automatic filling replenishing loom. When these filling carriers are placed in the magazine the ends extending therefrom have to be anchored so that when a filling carrier in the replenishing operation is transferred from the magazine to the lay of the loom, the end may be held until the first pick is laid by the fresh filling carrier. The operative, upon inserting the fresh filling carriers in the magazine, draws off an indeterminate length of the filling end and secures it, usually by a wrapping operation, to an end holder carried by the magazine. The operative usually, or at least not infrequently, thus draws off a length of filling end much greater than is necessary for anchorage on the end holder.

The object of the present invention is to provide cutting means adjacent the end holder by which the filling end extending from the point of anchorage on the end holder may readily be severed by the operative.

The nature and objects of the invention will appear more fully from the accompanying description and drawings and will be particularly pointed out in the claims.

The drawings illustrate a well known and familiar type of rotary filling carrier magazine such as is employed in the Northrop automatic filling replenishing loom. This device is illustrated for the purpose of disclosing a preferred embodiment of the present invention, but it will be understood that the invention is not restricted to the particular type of filling carrier magazine, nor to the particular construction illustrated, nor otherwise than as required by the claims.

As the general construction, operation and use of the filling carrier magazine illustrated is well known and familiar to

those skilled in the weaving art, it is unnecessary to illustrate and describe the same in detail or otherwise except in so far as to disclose the preferred embodiment of the present invention.

In the drawings:

Fig. 1 illustrates in front elevation and partially in central vertical cross section a rotary filling carrier magazine and a portion of the upper right-hand end of an automatic filling replenishing loom, together with a preferred embodiment of the present invention.

Fig. 2 is a detail in longitudinal cross section of the filling end holder and cutting means shown in Fig. 1.

Fig. 3 is a right-hand end elevation of the construction shown in Fig. 2.

Fig. 4 is a transverse section of the cutter blade.

In this type of loom a magazine stand 1 is rigidly supported from the breast beam 2 of the loom at the replenishing side. This stand carries a fixed laterally projecting stud 3, on which is rotarily mounted the hub 4 of the magazine. This magazine comprises two parallel disklike heads 5 and 6, each containing a peripheral series of seats, the former to receive the butts 7 and the latter the tips 8 of the fresh filling carriers 9. The magazine usually also comprises, secured to the hub 4, a flaring or bell-shaped head 10. The filling carriers are placed in a rotary series in this magazine and the magazine is rotated during the operation of the loom so as to maintain a fresh filling carrier at the bottom ready for transfer upon the call for filling replenishment.

Suitable end holding means are provided, usually in the shape of a stud 11 axially mounted in the outer end of the magazine. Each filling end 12, extending from a filling carrier 9 is brought down over the periphery of the bell-shaped head 10 and wrapped around the stud 11 to anchor it. Only a few turns of the filling end are necessary for this purpose, but the operative draws off from the filling carrier usually a much longer end than is necessary. After giving a few turns of this end around the stud 11, the operative is supposed to break off the remainder of the filling end and throw it away, but the operative, especially if the filling end is tough and hard to break, continues to wind the end upon the end holder.

Thus a large mass of filling soon accumulates on the end holder, which is undesirable. The present invention presents means by which the operative may readily sever 5 the filling end after it has been anchored on the end holder and thus prevent the overloading of the end holder with an unnecessary mass of filling.

In the construction illustrated, the stud 10 11 at its inner end 13 is shaped to fit in an axial opening in the hub 14 of the bell-shaped head 10 forming a part of the magazine, and is locked in position by a set screw 15. This stud is preferably provided at its 15 outer end with a radially projecting disk-like head 16.

The annular or preferably cup-shaped cutter holder is mounted on the outer end of the stud, preferably against the outer face 20 of the head 16 and preferably concentric with the stud. In the construction illustrated, this cutter holder 17 has an inwardly projecting hub 18 seating in an axial socket in the outer end of the stud and is held in place by a bolt 19 extending through the cutter holder and the stud. Recesses 20 are formed in the outer edge of the cutter holder, preferably at regular intervals. In the construction illustrated, where the cutter holder is shown as cup-shaped, the rim is inturned at 21 and the slots 20 extend through the rim. Suitable cutting means are provided exposing a cutting edge at each 30 of the slots. For this purpose there is preferably provided an annular cutter blade 22 held by the cutter holder and fitting against the inside of the holder between the in-turned rim 21 and the base 23 of the holder. This annular cutter blade is preferably 35 formed of a normally flat strip of steel sharpened at one, and preferably at both, edges and is maintained in its annular form by being sprung into position against the interior cylindrical surface of the cutter holder with its edges preferably abutting at 24. The annular cutter blade is rotarily 45 shiftable in the holder so as to bring a fresh cutting edge opposite the slots or recesses in the holder, and when it is sharpened at both edges, is also reversible in the holder 50 for the same purpose.

It will thus be seen that a filling end extending from any point of anchorage on the stud may readily be brought by the operative 55 preferably over the peripheral edge of the stud head 16 into contact with the cutter blade at one of the recesses or slots in the cutter holder and thus severed. The in-turned rim 21 obviates any danger of injury to the fingers of the operative because it prevents the fingers from coming into contact with the sharp edge of the cutter blade.

The operation of the device is now apparent. When the operative inserts a fill-

ing carrier such as 9 into the magazine, the end 12 extending therefrom is carried over the bell-shaped head 10, wrapped a few times about the stud, then carried over the stud head 16 and pressed against the cutter 70 blade in one of the slots or recesses. The position of the cutting device makes this a simple and natural operation, so that it is just as easy, if not easier, for the operative 75 to sever the end as it is to continue the winding unnecessarily upon the end holding stud.

The device is readily adapted to existing automatic filling replenishing looms. The provision for the rotary shifting of the cutter blade with respect to the slots or recesses in the holder and the preferable reversibility of the cutter blade insure a very long life to the cutter blade. Furthermore, it is a very simple matter to spring the cutter blade 85 out of the holder and substitute a new one therefor.

Having thus described the invention, what is claimed as new, and desired to be secured by Letters Patent, is:

1. A rotary filling carrier magazine having an axially projecting stud around which the filling ends extending from the filling carriers are wrapped to anchor them, an annular holder having recesses in its outer edge and concentrically mounted on the outer end of the stud, and cutting means mounted in said holder and presenting a cutting edge exposed in the recesses so that a filling end extending from any point of anchorage on the stud may readily be pressed against the exposed cutting edge and severed.

2. A rotary filling carrier magazine having an axially projecting stud around which the filling ends extending from the filling carriers are wrapped to anchor them, a cup-shaped cutter holder mounted concentrically on the outer end of the stud and having its rim inturned and slotted at intervals, and an annular cutting blade fitting against the inside of the holder between its base and inturned rim and exposing a sharp edge at each slot, whereby a filling end extending from any point of anchorage on the stud may readily be pressed against the cutting edge in one of the slots and severed.

3. A rotary filling carrier magazine having the construction defined in claim 2, in which the annular blade is normally a flat strip and is maintained in said annular form by the cutter holder.

4. A rotary filling carrier magazine having the construction defined in claim 2, in which the annular blade is rotarily shiftable in the cutter holder to expose fresh portions of the cutting edge through the slots.

5. A rotary filling carrier magazine having the construction defined in claim 2, in

which the annular blade is sharpened on both edges, is reversible to present either edge at the slots of the cutter holder and is rotarily shiftable in the holder to expose 5 fresh portions of either cutting edge at the said slots.

6. A rotary filling carrier magazine having an axially projecting stud around which the filling ends extending from the filling 10 carriers are wrapped to anchor them, a radially projecting head on the stud, an annular cutter holder slotted at intervals in

its outer edge and concentrically mounted on the outer face of said head, and cutting means mounted in the cutter holder and exposing a sharp edge at each slot, whereby a filling end extending from any point of anchorage on the stud may be brought over the edge of the stud head and pressed into a slot of the cutter holder against the cutting edge 15 and thus readily severed.

In testimony whereof, I have signed my name to this specification.

CARL D. BROWN.
